CITY

UNITED STATES PATENT OFFICE.

HERBERT B. NEWTON, OF BROOKLINE, MASSACHUSETTS.

BUILDING CONSTRUCTION.

Application filed December 13, 1919. Serial No. 344,572.

To all whom it may concern:

Be it known that I, HERBERT B. NEWTON, a citizen of the United States, residing at Brookline, in the county of Norfolk and 5 State of Massachusetts, have invented an Improvement in Building Constructions, of which the following is a specification.

My present invention relates to building construction employing molded building 10 blocks or bricks adapted to form a wall structure comprising an outer wall of blocks and an inner wall of blocks separated by an air space; and has more specific reference to a molded block and a tie-rod for connecting or tieing in the two walls.

An object of my invention is a tie-rod having engaging means with the blocks comprising the outer and inner walls that is simple and inexpensive in construction; that has 20 a relatively great bearing surface in the blocks; that admits of being cemented in place in the blocks to form, in effect, a unit structure; and that serves also to tie together the adjacent blocks in a course.

A further object of my invention is a 25 molded block having tie-rod receiving portions, and, more specifically, having complementary end portions which, when the blocks are laid in a course, cooperate to form 30 tie-rod receiving portions in which the tie-rod will be received to tie in the outer and inner walls and also the cooperating blocks.

The building block herein shown may be formed in the mold set forth in my co-pending 35 application filed December 13, 1919, Serial No. 344,571.

Fig. 1 is a plan view of a wall structure having an outer and an inner wall embodying my invention.

Fig. 2 is a sectional elevation of a portion 40 of the wall structure along line 2-2 of Fig. 1.

Fig. 3 is a perspective view of two blocks 45 of a course illustrating the tie-rod receiving recess formed in the end of a block and the complete tie-rod recess formed by the complementary recesses in the proximate ends of two blocks.

Fig. 4 is a side elevation of a molded block 50 formed in accordance with my invention.

Fig. 5 is a tie-rod embodying my invention.

As herein shown, the molded block 10 embodying my invention is preferably rectangular in form although it may be otherwise shaped. The blocks are laid in courses to

form the two spaced-apart walls *a* and *b* with the air space *c* therebetween.

The tie-rod, adapted to tie in the two walls, and also the adjacent blocks of a 60 course, is formed of a rod of suitable dimensions, and comprises the intermediate or shank portion 11, and the enlarged block-engaging end-portions 12 having the apertures 13 therein, formed by reflexing the 65 ends of the rod into, preferably, substantially circular form; or the tie-rod is formed with eyes as its end-portions which lie in the same plane. It is obvious, however, that the end portions of the tie-rod may assume 70 other forms.

The blocks are formed with suitable recesses therein to receive the end-portions of the tie-rod and, consequently, each block 10 is formed at each end with a semi-cylindrical recess 14 therein which extends preferably to the middle of the end faces thereof and terminates in a step 15 which is substantially flat to form a seat for the end portion of the tie-rods. The similar recesses in two 80 blocks, when placed end to end, as in a course, are adapted to cooperate to form a tie-rod receiving recess, one half of which is in each block. Rectangular recesses 16 are 85 formed in the each end face of the block the width of the cylindrical recesses 14 therein and extend therefrom to the same side face of the block; and said recesses 16 of adjacent blocks cooperate to form a channel in which the body or shank of the tie-rod is received. 90

The blocks are so laid to form the walls *a* and *b* that the joints between the blocks in the outer and inner walls come opposite each other or in line; or at least those blocks between which the tie rods are to be extended 95 are so arranged, and the tie-rods are placed in position with the end-portion 12 thereof in the recesses 14 between adjacent blocks, thereby to tie in the outer and inner walls and also to tie in the adjacent blocks of the 100 courses.

After the tie-rods are in place and before the next course of blocks are laid, the recesses in the blocks above the tie-rods are filled with mortar or cement thereby to seal 105 in the rods. The cement flows into the eyes or apertures of the tie-rod and unites with the block at the bottom of the recesses as well as with the side walls of the recesses above the tie-rods, thereby most effectively 110 seating in the tie-rods. The circular recesses extend to the middle of the blocks so

that the tie rods tie in a wall construction comprising two spaced tiers of blocks at the middle axes of the blocks so that there will be no tendency for the tie members to tilt the blocks, as would be the case if the tie members connected the blocks at either above or below the longitudinal axes.

Due to the shape of the ends of the tie rods a large bearing surface in the blocks is provided to resist either an outward or inward movement of the walls.

I claim:

1. A building block, having each of its end abutting faces formed for substantially half the height of such face with a semi-circular hollow which opens thru the top of the block and thru such face, that portion of the block from said hollow to the inner face of the block having a rectangular channel communicating with said hollow and of material less dimension than said hollow longitudinally of said block, whereby with two blocks in abutting relation there is formed a circular hollow having a reduced channel leading to one face of the blocks for the reception of cementitious material.
2. A wall construction comprising spaced tiers of blocks, the abutting edges of the blocks of one tier being opposite the abutting edges of the blocks of the other tier, the abutting edges of any two blocks of one tier being together formed with a recess opening thru the upper surfaces of the blocks and extended down into the blocks for substantially half the height of the blocks and spaced from the relatively inner surfaces thereof and with relatively narrow channels extending from said recesses to said inner faces, combined with metallic members fitting in said opposed recesses of the wall, extending thru and fitting said

channels and from one tier of blocks to the opposed tier.

3. A wall construction having spaced tiers of blocks, the vertical meeting faces of adjoining blocks being adapted to register and formed in each face with channels adapted when the blocks are in registry to provide an interlocking recess for the reception of a cementitious filling, said channels extended downwardly from the top faces of the block for substantially one half of the height of the block, and a metallic tie member having circular end-locking portions fitting in the opposed interlocking recesses of the respective tiers beneath said filling and adapted to unite the blocks at their middle portions thru their vertical end faces.

4. A wall construction having spaced tiers of blocks, the vertical meeting faces of adjoining blocks being adapted to register and formed in each face with channels adapted when the blocks are in registry to provide an interlocking recess for the reception of a cementitious filling, said interlocking recess extended downwardly from the top faces of the blocks for substantially one half of the height of the blocks, and a metallic tie member having circular end-locking portions fitting in the opposed interlocking recesses of the respective tiers beneath said filling and adapted to unite the blocks at their middle portions thru their vertical end faces, said tie member having an opening in the part adapted to seat in said recesses, whereby to cause the filling to interlock with said tie member.

In testimony whereof, I have signed my name to this specification.

HERBERT B. NEWTON.
